UNITED STATES PATENT OFFICE.

ALFRED M. A. BEALE, OF NEW YORK, N. Y.

TELEPHONE SYSTEM.

SPECIFICATION forming part of Letters Patent No. 356,300, dated January 18, 1887.

Application filed October 31, 1885. Serial No. 181,440. (No model.) Patented in England November 9, 1885, No. 13,575; in France November 30, 1885, No. 172,617, and in Belgium December 2, 1885, No. 71,066.

To all whom it may concern:

Be it known that I, ALFRED M. A. BEALE, of the city, county, and State of New York, have invented a new and useful Improvement 5 in Telephone Systems, of which the following is a specification.

My invention has been patented to me in the following foreign countries, to wit: in France on the 30th day of November, 1885, Patent 10 No. 172,617; in Great Britain on the 9th day of November, 1885, Patent No. 13,575; in Belgium on the 2d day of December, 1885, Patent No. 71,066.

My invention relates to an apparatus where- 15 by I may carry into practical effect a new improvement in the art of telephony, which improvement I have fully described and claimed in another application for Letters Patent filed simultaneously herewith and serially num- 20 bered 181,639. The said improvement in the art is herein disclaimed.

I propose to convey telephonic signals, including articulate speech, between distant points by causing variations in the electro- 25 static state of a body—such as a line-wire—extending between said points. I conduct no current whatever upon the line, but, on the contrary, the line is not in circuit with any source of electricity, being insulated at both 30 ends.

My invention differs in principle materially from known systems of telephony, as follows:

First. The so-called "Bell system" involves two magneto-telephones in circuit with a line. 35 No battery is here requisite, and hence normally there is no current on the line except when generated by the movement of the dia- phragm of the transmitter.

Second. The variable - resistance system, 40 which involves a transmitter containing bodies of conducting material, through which a battery - current passes and becomes modified. Here there is a constant current, upon which current are imposed variations or modifications through the action of the electrodes controlled by the voice.

Third. In my invention I employ no dynamic current upon the line, either permanent or temporary, although I may use a dynamic 50 current to charge the line; but the variations I produce are variations in the condition of

the body itself which forms the line—that is to say, I vary the electrostatic state of the line-conductor just as (to illustrate and assuming the possibility) I might vary its degree of 55 temperature or vary its strength as a magnet. I do not vary the condition of any current flowing over the line, for no current flows.

In the accompanying drawing, which is a diagrammatic view, A, represents the main- 60 line conductor. The terminals of this conductor are connected, respectively, to the plate B of the condenser C and the plate D of the condenser E. The opposing plate B' of the condenser C is connected to ground by the wire 65 F, and the opposing plate D' of the condenser E is similarly connected by the wire G to ground.

It will be apparent, therefore, that the plates B' D' are connected by ground and the plates 70 B D by the line-wire A, which line-wire thus substantially and in effect becomes a prolongation or bridge between said plates B D. It will also be obvious, inasmuch as, owing to the usual and ordinary construction of condensers, there exists between the plates B and 75 B' and D and D' a layer of dielectric or insulating material, that the entire line-wire A is insulated, and that hence no direct dynamic current can either pass upon or from it, nor 80 can any such current circulate therein, inasmuch as said wire A is not a part of a circuit capable of conducting such a current. If, now,

a charge of electricity be conducted to the plate D' of the condenser E, this plate will be- 85 come statically charged, and will induce a cor- responding charge upon the opposite plate, D, across the intervening dielectric, and inasmuch as the line-wire A is substantially part of the plate D, said charge will also be induced 90 on said wire and the plate B of the condenser C. The charge induced upon the plate B will in turn induce a corresponding charge upon the plate B', which communicates with ground.

As long as the original inducing-charge is 95 maintained on the plate D' of condenser E for so long will the condition of affairs above set forth continue; and if this charge is supplied by a galvanic battery the wire will, other things being equal, remain in its charged state 100 so long as this battery-current remains constant. If, however, the inducing-charge is not

constant, but variable, then the induced charge on the line will, in like manner, vary, and hence by controlling and varying the character of the inducing-charge I can correspondingly control and vary the electrostatic condition of the line.

H is a telephone-transmitter containing electrodes and of any known construction, which I arrange with a battery in the closed local circuit I. Said circuit includes the primary J of an induction-coil, the secondary K of which coil is in communication at one end with wire G and at the other end with the earth.

15 When speech is uttered before the transmitter H, the battery-current in the local circuit I is modified, and in proportion to the variations of strength of said current induced charges of high potential are generated upon 20 the secondary K. These induced charges charge the condenser E, and hence the line A. Inasmuch as the current in the local primary circuit I will correspond in its characteristics to the rate, amplitude, and frequency of the 25 sound-waves which modify the current through the agency of the transmitter, so will the current thus varied in turn induce a charge of electricity on the secondary wire K, which will charge the condenser, and hence the line, 30 at a rate with a frequency and to an extent corresponding to the original sound-vibrations. When, however, the current in the local circuit I ceases, then whatever charge has accumulated on plate D disappears by 35 reason of the earth-connection. I thus obtain a line varying in electrostatic state or condition correspondingly to the sound-waves affecting the transmitter, and the variations in the electrical condition of the line will induce corresponding variations in the electrical condition 40 of the plate B' of the condenser C, and hence of the wire F, communicating from said plate B' to ground. It remains then to con-

nect a receiving-telephone, N, to the wire F, and this I prefer to do by attaching said wire 45 to one end of a coil, L, which coil forms the secondary wire of an inductorium, of which the primary wire M is in a local circuit, I, with the receiver N. The other end of coil L connects to ground.

50 In practice, in order that a transmitter and a receiver may exist on each end of the line, I arrange the transmitter in local circuit and the receiver in shunt-circuit therefrom, as indicated at H H' and N N'.

55 I claim as my invention—

1. The combination of a main line connected at each end to an induction-plate, induction-plates in inductive proximity to but separated by a dielectric from said first-mentioned plates, 60 conductors connecting said last-mentioned plates to ground, the secondary coil of an inductorium in each of said conductors, a local circuit containing a telephone-transmitter, a source of electricity, and the primary coil of 65 one of said inductoriums, and a local circuit containing the primary of the other of said inductoriums and a receiving-telephone, substantially as described.

2. The combination of a main line connected 70 at each end to an induction-plate, induction-plates in inductive proximity to but separated by a dielectric from said first-mentioned plates, conductors connecting said last-mentioned plates to ground, the secondary coil of 75 an inductorium interposed in each of said conductors, and two local circuits, each respectively containing the primary coil of one of said inductoriums, a source of electricity, a transmitting-telephone, and in shunt-circuit 80 a receiving-telephone, substantially as described.

A. M. A. BEALE.
